Application May 19, 1933, Serial No. 671,920
In Sweden April 7, 1931

5 Claims. (Cl. 217—7)

The present invention refers to a structural member particularly suited for the production of walls, such as partitions adapted to form compartments in boxes, on shelves or the like, the 5 invention making it possible, with the use of a suitable number of such members, to provide a longitudinally accurately adjustable wall in a simple manner without great cost and inconvenience.

10 The structural member according to the invention refers to that type of members which is provided at the one or both ends with grooves cooperating with connecting tongues engaging the grooves, which tongues may each be provided on 15 the corresponding end portion of the adjacent member, or may constitute separate, isolated parts, the arrangement being such that a suitable number of members succeeding one another longitudinally form together a wall adapted to be 20 shut together or extended in the same direction, which wall can, before it is fixed by securing the members to each other or to a sub-structure, be accurately adapted with respect to the desired length thereof through mutual displacement of 25 the members. The invention is substantially characterized in that each of the grooves located between the lateral limiting surfaces of the structural members is closed at the top by a part forming a cover over the groove.

30 The accompanying drawing illustrates a few embodiments of members and of partitions composed of such members according to the present invention. Fig. 1 is an elevation of a member according to one embodiment of the invention, and 35 Fig. 2 is a cross section thereof on line II—II in Fig. 1. Fig. 3 shows a partition arranged on a substructure and composed of members according to Figs. 1 and 2. Figs. 4 and 6 are elevations of the member according to two further embodiments, and Figs. 5 and 7 represent cross sections thereof on lines V—V and VII—VII in Figs. 4 and 6 respectively. Fig. 8 is an elevation of a member according to a fourth embodiment, and Fig. 9 is a longitudinal section thereof on line IX—IX in Fig. 8. Fig. 10 is a perspective elevation of a member according to a further embodiment of the invention, the parts of the member being separated. Fig. 11 is a plan view of a partition composed of members, for instance according to 50 Fig. 10, and formed with transversal portions.

The member shown in Figs. 1 and 2 consists of four rectangular parts formed out of a sheet material, such as wood, paste-board or the like, three of which parts are preferably made to exactly the same size and joined with each other, as shown in the drawing, with the one part, sheet 1, projecting for a distance in between the two other sheets 2 and 3 forming the lateral limiting surfaces of the member, so that a groove 4 is 55 formed in the one end portion of the member,

said groove extending all over the height of the member, while at the other end of the member is formed a connecting tongue 1 corresponding to the groove. The groove formed between parts 2 and 3 is closed at the top, according to the invention, by the fourth part secured to the end surfaces of the first-mentioned parts and forming a plate 5 covering the groove.

The groove 4 in the one end of the member thus produced will thus have exactly the same 10 dimensions as the connecting tongue located at the other end of the member, which results in that a requisite number of such members may be combined to form a partition (see Fig. 3) in that the respective connecting tongue is introduced 15 from below or from the one end into the groove 4 of the adjacent member. After the members have been combined they will be displaceable longitudinally relatively to each other and will also be guided transversely. The partition thus 20 composed will also be provided with a groove in its one end and with a connecting tongue at its other end. It is preferred, before the partition composed from the members is secured in its place, to provide the last-mentioned end portion 25 with a separate part having one groove only, which latter part may be made from the same kind of sheets 2, 3 and 5 as the members, while lacking the laterally projecting tongue 1, which 30 tongue may be replaced by an intermediate member separating the sheets 2 and 3 and secured to the one end edge thereof. Before the partition thus composed is fixed by the members being 35 secured to each other, or is attached, for instance with the aid of glue, with the lower side to a sub-structure 6, the length of the partition may be accurately adapted by a suitable mutual displacement of the members.

The embodiment of the member illustrated in 40 Figs. 4 and 5 differs from the member according to Figs. 1 and 2 only in that the sheets 2, 3 and 5 are replaced by a part 7 formed through bending, the bent portion 8 of which part corresponds 45 to the sheet or plate 5. The part 7 may be bent and secured in any suitable manner, for instance by being glued to the connecting tongue 1, through which attachment the part 7 maintains 50 its bent shape if it is made from resilient material, for example. The connecting tongue 1 may also be formed from a double-folded sheet mate-

rial.

A development of the latter embodiment is represented by the member illustrated in Figs. 6 and 7, where the connecting tongue 10 of the member 9 is also made as a bent part forming a direct extension of the member integral therewith. This member with its connecting tongue 55 is preferably pressed out of sheet metal, the connecting tongue being compressed to a greater extent than the member proper with the outer 60

width and height corresponding to the inner width and height of the member, so that the connecting tongue will fit into the groove of an adjacent member, as in the preceding embodiments. 5 Preferably, the lower edge 11 of the member is then bent outwardly to facilitate the introduction of the tongue into the groove.

According to the modified embodiment of the member according to the invention as shown in 10 Figs. 8 and 9, each such member 12 is formed out of a single, substantially L-shaped piece stamped out of sheet metal or the like, which piece has been given, through suitable bending, the shape illustrated in said figures, which shape corresponds substantially to the shape of the embodiment illustrated in the previously described Figs. 15 4 and 5. Thus the one end is provided with a tongue 1 and the other with a groove 4 to receive the tongue of another member. To facilitate securing of the members to their sub-structure, if such securing is intended to take place, the lower edges of the forked part forming the groove 4 may be bent upwardly, if desired.

The embodiment shown in Fig. 10 differs from 20 the preceding ones in that the tongue of a member is replaced by a loose or removable connecting tongue 13 having a rectangular cross-section all over the length thereof. The other members 25 14 cooperating with the first-mentioned members are of a forked cross-section at both ends. The latter members 14 are formed from two opposed rectangular sheets 15, 16 of an equal size with an intermediate member 17 separating said sheets and keeping them together at the central portion thereof, and from a plate 18 covering their upper side entirely.

An example of the employment of the above 30 described members for composing partitions with transversal portions or portions which cross one another is illustrated in Fig. 11. The members are united with each other, as indicated hereinbefore, by introducing the connecting tongues into the grooves of the members, whereupon the latter are displaced relatively to each 35 other, until the respective walls or partitions have been properly adapted as to their length, after which these walls or partitions are secured to each other or to a rigid sub-structure. Connecting pieces of any suitable form may be arranged at corners or crossings to keep the wall 40 portions together. The corner which is formed between the walls 19 and 20 is constituted by an angle piece 21 made, for instance, of solid material, and the angle shanks of which form connecting tongues entering the grooves of the members adjacent to the corner. The walls 19, 45 20 crossing each other are connected with one another by means of a cross piece formed out of two tongues 22, 23 joined with each other 50 in any suitable way and made from bent sheet metal, for example, while the wall 25, which terminates adjacent to the wall 19, is kept together with the latter by means of connecting tongues, which in the embodiment shown constitute parts 55 of a T-piece 26 made from bent sheet metal material, which T-piece, however, may be made in any suitable manner, like the other connecting pieces for corners and crossings.

The invention is obviously not limited to the 60 embodiments illustrated in the drawing. Each member may, for instance, be made integral

with the tongue by being formed from a plastic material which has been given the requisite hardness through a suitable treatment after the forming thereof. For the securing of the members to each other or to the sub-structure upon adjustment of the wall, means of any suitable kind, such as adhesives, screws, nails or the like may be brought into use. In the embodiments where the member consists of bent sheet-metal material, such material may have resilient properties of 10 such a nature, or may be made in such a manner, as to be retained through the resiliency at the connecting tongue in a sufficient degree, without the aid of other connecting means. In addition to serving as partitions to form compartments and so forth, the bodies formed from the longitudinally composed members displaceable relatively to each other may also be utilized in a number of further applications where a quick and accurate adjustment of the length of these bodies 15 is desirable.

What I claim is:—

1. Structural members adapted particularly for the production of walls, such as partitions to form compartments in boxes, on shelves or the like, each of said members being provided in the one or both ends with grooves cooperating with connecting tongues engaging the grooves, the arrangement being such that a suitable number of members succeeding one another longitudinally form together a wall adapted to be shut together or extended in the same direction, which wall can, before it is fixed by securing the members to each other or to a sub-structure, be accurately adapted with respect to the desired 30 length thereof through mutual displacement of the members, characterized in that each of the grooves located between the lateral limiting surfaces of the structural members is closed at the top by a part forming a cover over the groove 40 and open at the bottom, in order to enable the structural member as well as the connecting tongues to rest directly upon a sub-structure.

2. A structural member according to claim 1, characterized by the same consisting of four rectangular parts rigidly joined together and formed out of sheet material.

3. A structural member according to claim 1, characterized in that the member is made from a flexible or resilient material, said material being bent to fork-shape and provided with a sheet-like connecting tongue introduced into the end of the groove thus formed for a portion of the length of the groove, said connecting tongue being formed out of a double-folded sheet material, if desired.

4. A structural member according to claim 1, characterized in that the member is made integral with the connecting tongue, and is bent to fork-shape together with the connecting tongue, which latter is adapted to be introduced into the groove of another member.

5. A structural member according to claim 1, characterized in that the member is formed from an L-shaped piece, and forked cross section 65 along the whole length of the grooved portion, and in that the foot of the L-shaped piece constitutes a tongue which may be introduced into the groove of another member.
